UNITED STATES PATENT OFFICE.

CHARLES H. J. DILG, OF NEW YORK, N. Y.

GUARD FOR ROTARY FANS AND THE LIKE.

1,290,721.

Specification of Letters Patent.

Patented Jan. 7, 1919.

Application filed October 9, 1917. Serial No. 195,500.

To all whom it may concern:

Be it known that I, CHARLES H. J. DILG, a citizen of the United States, residing at the city of New York, in the borough of 5 Manhattan and State of New York, have invented certain new and useful Improvements in Guards for Rotary Fans and the like, of which the following is a full, clear, and exact description.

10 My invention relates to guards for rotary fans and the like. An object of my invention is to provide a guard which will be light and of simple construction and convenient to assemble and will be strong and 15 durable and able to withstand the rough usage to which guards are subjected. Another object is convenience in attaching a name or cover plate to give a finished appearance to the structure. Other objects and 20 advantages of my invention will appear from the following description.

In accordance with my invention, I secure the radiating wire spokes of such a guard to a central attaching plate which 25 affords a support for the spokes at two points, the outer support being designed to clamp a considerable length of the spoke and the inner support being a perforation engaged by the inner end of the spoke, 30 which preferably passes through the perforation and has a substantial length bent back against the face of the plate. An extremely rigid structure is thereby obtained. The outer clamp may conveniently be an 35 integral ear of substantial length perforated near its inner end for the reception of the spoke and bent down upon the spoke. The cover plate comprehended within my invention is of the proper size to cover the 40 attaching plate with the exposed protruding ends of the spokes and has a plurality of flexible fastening ears turned over the periphery of the attaching plate in locking engagement therewith. My invention also 45 comprehends other features of construction as will hereinafter more fully appear.

I shall now describe the illustrated embodiment of my invention and shall thereafter point out my invention in claims.

50 Figure 1 is a side elevation of a complete electric fan including an embodiment of my invention;

Fig. 2 is a transverse central sectional elevation of the guard;

55 Fig. 3 is an enlarged detail of a portion of the intermediate ring;

Fig. 4 is an enlarged inner face view of the attaching plate with portions of the radiating spokes, as indicated by line 4-4 of Fig. 2, looking toward the left. 60

I have illustrated my invention in connection with an electric fan driven by an ordinary electric motor in the casing 1 which is mounted upon the base 2. The rotary fan is mounted on a hub 3, which is secured on 65 the armature shaft, and the guard is attached to the casing of the motor.

My improved guard is preferably composed of wire and comprises a number of radial spoke members which are suitably 70 secured at their outer ends and are secured together at their inner ends by an attaching plate which provides a two-point bearing for the spokes, one a clamp which embraces and extends along the spoke for 75 some distance, and the other a perforation through which the spoke passes. In the specific illustrated embodiment of my guard, eight radiating wire spoke members 4 are provided of any usual or suitable 80 shape, the outer ends of which are bent at an angle so that the component members together form a cage or protective device of usual shape. The outer ends of the spoke members 4 are secured in any suitable way 85 to a connecting ring 5, which is attached to the motor casing 1 by supporting arms 6. Also at the front of the guard near its periphery the spokes 4 are coiled around an intermediate stiffening ring 7, which also 90 serves to properly space the spokes. To this end the intermediate ring 7 is provided with a bend 8 (see Fig. 3) for each spoke, and the spokes encircle the intermediate ring at these bends 8 and are thereby prevented 95 from traveling around the ring, and are hence kept properly spaced.

At their inner ends the spokes are secured by an attaching plate 9 which provides two points of attachment for each spoke. The 100 outer attachment comprises a perforated, flexible clamping ear 10, of which there are eight provided about the periphery of the attaching disk 9 properly spaced for the reception of the spokes, and which initially extend rearwardly at right angles to the plane of the attaching disk 9. Radially inward from these ears 10, the disk 9 is provided with a corresponding number of spoke-receiving holes or perforations 11, and the wire 110 spokes are passed through the perforations in the ears 10 and their inner ends are then

passed outwardly through the perforations 11 and then bent down along the front of the attaching disk 9, as shown in Fig. 2. The clamping ears 10 are bent down upon the wire spokes 4 and are of sufficient length to extend a substantial distance along the spokes. A two-point bearing is thus provided for the inner end of each spoke member, and the ears 10, by reason of their 10 length, constitute extremely efficient clamps and lend great rigidity to the structure. The guard is thus made strong and durable, while the simplicity of the attaching means renders the device very easy to assemble.

15 To provide a finish to the structure as well as to protect the free ends of the wire spokes from accidental injury, I provide means for covering up the exposed ends consisting of a cover plate or disk 12. This cover plate is 20 provided with a plurality of flexible attaching ears 13 extending inwardly about the periphery of the cover plate, and the cover plate is of such shape that the attaching ears 13 just fit about the attaching 25 plate 9, and the cover plate is attached by bending these ears 13 over the periphery and down along the rear face of the attaching disk 9, thereby securing the cover plate in place. This cover plate may be ornamental, 30 and, if desired, may be used as a name plate, thereby giving an ornamental finish to the guard.

It is obvious that various modifications may be made in the construction shown in 35 the drawings and above particularly described within the principle and scope of my invention.

I claim:

1. A guard for electric fans or the like, 40 comprising radial spoke members, means joining the outer ends of the spoke members, and an attaching plate for the inner ends of the spoke members having a double support for each spoke comprising at the outer 45 edge of the plate a clamp engaging a substantial length of the spoke and an inner perforation engaged by the inner end of the spoke.

2. A guard for electric fans or the like, 50 comprising radial spoke members, means joining the outer ends of the spoke members, and an attaching plate for the inner ends of the spoke members having for each spoke member an outer locking ear of substantial 55 length perforated near its inner end and an inner spoke-receiving perforation, the spokes passing through their respective perforated ears and having their ends secured in the respective spoke-receiving perforations and 60 the ears being turned down upon the spokes.

3. A guard for electric fans or the like,

comprising radial wire spoke member, means joining the outer ends of the spoke members, and an attaching disk for the inner ends of the spoke members having for each spoke 65 member an outer integral locking ear of substantial length perforated near its inner end and projecting from the periphery of the disk and an inner spoke-receiving perforation, the spokes passing through their respective perforated ears and having their ends inserted through the respective spoke-receiving perforation and bent back on themselves against the face of the plate and the ears being bent down upon the spokes. 70 75

4. A guard for electric fans or the like comprising radial spoke members, means joining the outer ends of the spoke members, an attaching disk for the inner ends of the spoke members, and a cover plate for the 80 attaching disk having a plurality of flexible fastening ears turned over the periphery of the attaching disk in locking engagement therewith.

5. A guard for electric fans or the like, 85 comprising radial spoke members, means joining the outer ends of the spoke members, an attaching plate for the inner ends of the spoke members having a double support for each spoke member comprising a clamp 90 engaging and extending a substantial distance along the spoke member and a spoke-receiving perforation, and a cover plate for the attaching plate having a plurality of flexible fastening ears turned over the periphery of the attaching plate in locking engagement therewith. 95

6. A guard for electric fans or the like, comprising radial wire spoke members, means joining the outer ends of the spoke 100 members, an attaching disk for the inner ends of the spoke members having for each spoke member an outer integral locking ear of substantial length perforated near its inner end and projecting from the periphery 105 of the disk and an inner spoke-receiving perforation disposed in substantially radial alignment inwardly from the locking ear, the spokes passing through their respective perforated ears and having their ends inserted through the respective spoke-receiving perforation and bent back on themselves against the outer face of the plate and the ears being bent down upon the spokes, and a cover plate for the attaching disk having a plurality of 110 flexible fastening ears projecting from its inner face and turned over the periphery of the attaching disk in locked engagement therewith. 115

In witness whereof, I subscribe my signature. 120

CHARLES H. J. DILG.
